UNITED STATES PATENT OFFICE.

SETH E. PERKINS, OF WATERLOO, IOWA, ASSIGNEE TO PERKINS ELECTRIC DOOR CONTROL COMPANY, OF WATERLOO, IOWA.

DOOR-CONTROLLING DEVICE.

1,326,286.

Specification of Letters Patent. Patented Dec. 30, 1919.

Application filed April 26, 1919. Serial No. 292,923.

To all whom it may concern:

Be it known that I, SETH E. PERKINS, a citizen of the United States, residing at Waterloo, in the county of Blackhawk and State of Iowa, have invented a new and useful Door-Controlling Device, of which the following is a specification.

This invention relates to improvements in door controlling devices, the object of the invention being to provide an improved door control operated by a motor that is carried directly by the door, and which device is so constructed that the motor may continue to rotate while the door remains stationary without injury to the motor.

A further object of the invention is the provision of a device of the character set forth that may be applied to any swinging or sliding door without the necessity of making any change in the structure of the door or the manner in which it is hung, and which device is comparatively simple in construction and economical to manufacture.

With the foregoing and other objects in view, which will appear as the description proceeds, the invention consists in the novel features of construction and combination of parts which will be more fully described hereinafter and particularly pointed out in the claims.

The drawing accompanying and forming part of this specification is a perspective view, partly broken away, illustrating the application of my improved controlling device on a swinging door.

Referring to the drawing, 2 designates a pair of doors, to one of which the controlling device is applied. The device in the present instance comprises a base plate or board 3, which may be of any suitable size to adapt it to the particular door on which it is to be used. At one end of the board is mounted a small motor 4 having a shaft 5 extending therefrom toward the opposite end of the board, a bracket 6 being secured to the board and having an upturned perforated ear 7 providing a bearing for said shaft. The bracket 6 also carries a pair of upstanding perforated ears 8 at right angles to the ear 7, forming bearings for a short shaft 9, at one end of which is secured a pulley 10 so located as to project beyond the edge of the door to which the device is applied. The shaft 9 is adapted to receive rotary motion

from the shaft 5 of the motor, a suitable reducing gearing being interposed between such shafts. In the present instance this reducing gearing is shown as comprising a bevel gear 11 secured on the shaft 9 and adapted to mesh with a bevel pinion 12 carried by the motor shaft 5, the relative sizes of the pinion and gear being such that the speed of rotation of the shaft 9 is considerably reduced as compared with that of the motor shaft 5. The board is provided with a plurality of openings 13 by means of which it may be secured to the door by screws or bolts and nuts. Around the pulley 10 is passed a cable 14, one end of which is secured at a suitable point on the door-frame and the opposite end to some other fixed point at an angle to the door opening, as for instance an adjacent wall as shown in the drawing, the tension of the cable being just sufficient to operate the door when the motor is started. The motor may be placed in electrical connection with any convenient source of power (not shown) and push buttons located at any convenient point, as shown at 15, for opening and closing the circuit to the motor. A reversing switch, such for instance as that shown in my co-pending application, Serial No. 292,929 filed Apr. 26, 1919, may be secured on the board 3, as shown at 16 and adapted to automatically reverse the direction of rotation of the motor when the door has reached either extreme open or closed position. The motor, reducing gear and switch are all mounted on the base board and completely wired ready to be attached to either sliding or swinging doors.

From the foregoing it will be seen that, as the cable is comparatively slack on the pulley, should any obstacle be encountered by the door in its swinging or sliding movement the motor can continue to rotate, since the pulley will rotate loosely in the loop of the cable, whereby the burning out of the motor before the obstruction can be removed is prevented. It will also be seen that in the use of this device the necessity of using a latch for holding the door closed is eliminated, since the cable passing around the pulley will hold the door closed or at any point desired when the operation of the motor ceases.

While I have described in detail the struc-

ture herein illustrated, it is to be understood that I do not thereby limit my invention to the precise features of construction shown, as I am aware that many mechanical changes may be made therein without departing from the spirit and scope of the invention as set forth in the appended claims.

Having thus described my invention, what I claim is:

- 13 1. A door-controlling device, comprising a base board adapted to be mounted on the door and to travel therewith, a motor carried by said base board, and means carried by the board and adapted to be operated by the motor for opening and closing the door, said means being also adapted to permit operation of the motor without operating the door.
- 15 2. A door-controlling device, comprising a base board adapted to be mounted on the door and to travel therewith, a motor carried by said base board, means carried by the

board and adapted to be operated by the motor for opening and closing the door, and means also carried by the board for reversing the direction of rotation of the motor when the door has reached the extreme limits of its open or closed position.

3. A door-controlling device, comprising a base board adapted to be secured to the door, a motor mounted thereon, a shaft mounted on said board and having a pulley secured thereto, gearing between said shaft and the shaft of the motor, and a cable passing around said pulley and having its ends secured to fixed points.

In testimony that I claim the foregoing as my own, I have hereto affixed my signature in the presence of two witnesses.

SETH E. PERKINS.
